UNITED STATES PATENT OFFICE

2,045,577

WELT BUTTING MACHINE

Benjamin B. Blanchard, Swampscott, Mass., assignor to United Shoe Machinery Corporation, Paterson, N. J., a corporation of New Jersey

Application May 1, 1933, Serial No. 668,829

15 Claims. (Cl. 12—67)

This invention relates to machines for operating upon boots and shoes and is illustrated as embodied in a machine of the type shown, for example, in United States Letters Patent No. 1,614,836, granted January 18, 1927, on an application of George Goddu, and No. 1,709,347 granted April 16, 1929, on an application of George Goddu and Fred L. Mackenzie. Such machines are designed for butting the welt of a welted, unsoled shoe preparatory to the sole laying operation and 5 tacking the margin of the upper to the insole in the region of the heel breast line. Such machines include devices for supporting a shoe, means for locating and supporting the welt ends during the butting operation, cutters for butting 10 the welt comprising a stationary anvil and a movable knife arranged to shear off the welt at the end of the inseam, and tackers for securing the upper to the insole.

The location of the tacks which secure the margin of the upper to the insole must be effected with considerable precision if these tacks are most effectively to serve their purpose, namely, to secure in lasted position that portion of the upper in the region of the heel breast which is not held in position by the inseam or the heel seat lasting tacks. The range within which these tacks are located longitudinally of the shoe bottom is less than one-half inch and most of 15 this space is taken up by the anvil during the welt butting operation. It is, therefore, desirable to move the anvil from its operative position before the tacking operation.

It is an object of this invention to provide a 20 machine of the type set forth in the patents above referred to which, without sacrificing any of the advantages of prior constructions of this type, provides an organization which permits the location of the tacks above referred to at any 25 point between the end of the inseam and the end of the line of heel seat tacks. Accordingly, a feature of the invention consists in the provision, in combination with the tack driving mechanism of a welt butting machine, of co- 30 operating welt butting cutters, for example, the knife and the anvil of the illustrated machine, both of which, during the welt butting operation, are positioned in alinement with the fastening means and both of which are movable 35 out of alinement with said fastening means after the welt has been butted and before the fastener is inserted. In the illustrated machine, the movement of the knife out of alinement with the fastening means is a continuation of its operating 40 movement after the welt has been butted,

and the movement of the anvil out of alinement with the fastening means is widthwise of the shoe, such movement of the anvil being effected by means operable by the knife actuating mechanism.

A further feature of the invention comprises an organization including a crease finder movable with the tacker transversely toward and from the shoe and adjustable relatively to the tacker in the direction of movement of the crease finder and a gage for locating the crease finder in any one of a series of predetermined positions relatively to the tacker. As illustrated, the gage consists of an axially mounted polygonal block 10 the edge faces of which are arranged at varying 15 distances from the axis of the block.

These and other features of the invention, including certain details of construction and arrangement of parts hereinafter set forth, will now be specifically described with reference to 20 the accompanying drawings and pointed out in the appended claims.

In the drawings,

Fig. 1 is a front elevation of a welt butting machine embodying the features of the present 25 invention;

Fig. 2 is a broken plan view taken substantially in the plane of the bottom of a shoe held in position to be operated upon;

Fig. 3 is a plan view similar to Fig. 2, showing 30 the operating instrumentalities as they are arranged at the end of the cycle of operations and before they are returned to their respective initial positions;

Fig. 4 is a detail front elevation illustrating 35 particularly the welt supporting assembly at one side of the shoe;

Fig. 5 is a sectional elevation taken substantially on the line V—V of Fig. 2;

Fig. 6 is a sectional elevation taken substantially on the line VI—VI of Fig. 2;

Fig. 7 is a perspective view of the knife carrying mechanism from which the anvils are operated; and

Fig. 8 is a perspective view of the combined 45 welt support and anvil carrier.

The general organization of the illustrated machine is substantially the same as in the machine disclosed in the patent to Goddu and Mackenzie, above referred to, to which reference 50 may be had for a description of details of construction not disclosed herein.

Referring to Fig. 1 the illustrated machine is provided with a pair of shoe supporting members 10, and a back stop 12 arranged to take the 55

force of the cutting stroke of the welt butting knives 14. The heel seat of a shoe to be operated upon is located at a predetermined elevation by a hold-down member 16. The welt at each side 5 of the shoe is supported for the butting operation by a crease finder 18, (Fig. 2) an anvil 20, and a welt support 22 which, together with the knives 14 and a pair of tackers 24 (Fig. 1) are mounted in a pair of swinging frames 26 ful- 10 crumed at 28 to vertical shafts journaled in the machine frame. When the machine is at rest the swinging frames 26 are in their open position, as shown in Fig. 1. When the machine is started the swinging frames 26 are automatically swung 15 inwardly thereby causing the crease finders 18 to engage in the welt crease at opposite sides of the shank of the shoe and thus to urge the margin of the upper and the parts stitched thereto inwardly over the last bottom. The unlasted portions 20 of the upper between the ends of the inseam and the ends of the line of heel seat tacks are thus urged inwardly over the last bottom and held in position for the reception of tacks 30 (Fig. 3) which are driven by the tackers 24 after 25 the welt has been butted and after the anvils 20 have been withdrawn transversely of the shoe in order to bring them out of alignment with the tackers.

The following description is confined to one 30 of the swinging frames 26 and the parts assembled therein but it will be understood that the description is equally applicable to the opposite swinging frame assembly.

Referring now more particularly to the construction and arrangement of the anvil 20 said anvil is arranged to overlie the shoe bottom and its upper surface is in the horizontal plane in which the welt butting knife 14 moves as it advances to butt the welt. The forward upper edge 40 of the anvil forms a stationary cutting element which co-operates with the knife to impart a shearing cut to the welt. The forward edge face of the anvil 20 engages the rear edge face of the crease finder 18 (Fig. 2) and the rear edge face 45 of the anvil engages the forward edge face of the welt support 22. The upper surfaces of the crease finder, the anvil, and the welt support form a substantially continuous, unbroken surface over which the end of the welt travels as the shoe is 50 inserted into the machine. The forward edge face of the anvil at its inner end serves as an abutment to arrest the movement of the shoe and to gage its operative position by engagement with the end of the inseam. The anvil is 55 provided with a shank 32 (Fig. 5) which is offset downwardly therefrom and slidably mounted upon a carrier 34 which carrier is formed integrally with the welt support 22 and downwardly offset therefrom (Fig. 8). The rear side of the 60 shank 32 of the anvil is provided with a tongue 36 (Fig. 6) which is arranged to slide in a transverse groove 38 formed in the carrier 34. The carrier 34 is extended forwardly at 39 to provide a support for a shank portion 40 arranged to ex- 65 tend outwardly from the crease finder 18, said shank being arranged to embrace the end of the forward extension of the carrier 34 and to slide thereon toward and from the shoe (Fig. 6). Preferably, the front face of the shank 32 of the 70 anvil is offset forwardly from the front edge face of the anvil (Fig. 3) and the rear face of the shank 40 of the crease finder 18 is offset forwardly from the rear edge face of the crease finder to the same extent as the offset provided 75 in the shank 32.

The anvil 20 is withdrawn from its operative position, prior to the actuation of the tacker 24, by a power-operated slide 68 (Fig. 7) which actuates a knife carrier 70. As illustrated, the connection between the power operated slide 68 and the anvil comprises a cam lever 50 (Fig. 2) having pin and slot connections with the slide 68 and the shank 32 of the anvil, respectively. Accordingly, there is provided at the outer end of the shank 32 of the anvil a pin 42 (Fig. 5) arranged to extend into a recess 44 formed in the carrier 34 (Fig. 8). A roll 46 is carried by the pin 42 for engagement within a slot 48 in the cam lever 50. The cam lever is fulcrumed on a headed stud 52 (Fig. 4) projecting upwardly from an upstanding boss 54 formed in an arm 56. The arm 56 is secured by a split clamp 58 to a headed stud 60 extending downwardly from a forwardly extending arm 62 of the carrier 34. The cam lever 50 is supported upon a surface 64 which extends from the forward end of the arm 62 rearwardly to the rear edge face of the carrier 34 (Fig. 8). The surface 64 extends inwardly to the base of an arcuate groove 66 and outwardly to the end of the carrier 34. The upper wall of the 25 groove 66 provides an abutment which holds the cam lever 50 from vertical movement. In order to provide clearance for the pin 42 and roll 46 as they move inwardly to return the anvil 20 to its initial position, the upper wall of the groove 30 66 is cut away at 67, as shown in Figs. 2 and 8. The cam lever is actuated by the power operated slide 68 (Fig. 7) which is arranged to move rearwardly of the machine in a horizontal plane in order to draw the welt butting knife 14 through 35 the welt. The power operated slide has an inclined sliding connection with the knife carrier 70. Projecting downwardly from the knife carrier is a pin 72 the upper end of which provides a fulcrum for a cam actuated lever 74 which actuates a chip remover 76 (Fig. 1). Mounted on the downward extension of the pin 72 is a cam roll 78 which travels in a cam slot 80 in the lever 50, the cam roll being of sufficient length to remain in the cam slot during the vertical movement of the knife carrier 70. The arm 56 (Fig. 4), to which is clamped the stud 52 on which the cam lever 50 is fulcrumed, is spaced downwardly from the extension 62 to which said arm is secured sufficiently to permit the pin 72 to clear 40 the arm as the pin moves forwardly and downwardly with the knife carrier 70 (Fig. 7).

The location of the tack 30 transversely of the shoe bottom is determined by the crease finder 18 which engages within the welt crease of the shoe and thereby locates the tacker 24 transversely of the shoe bottom. In order to vary the location of the tack 30 transversely of the shoe bottom the crease finder is adjusted transversely of the shoe by sliding the shank 40 of the crease 55 finder upon the forward extension 39 of the carrier 34. In order to secure the crease finder in adjusted position a clamping screw 92 is arranged to extend through a slot 94 (Fig. 4) in the shank 40 and has threaded engagement within a tapped 60 bore in the carrier 34.

In order to gage the adjustment of the crease finder 18 a polygonal block 96 is axially mounted on the screw 92. As illustrated, the polygonal block 96 is substantially a regular octagon 70 and its axis is so located that the edge faces of the block are arranged at progressively varying distances therefrom. As shown in Fig. 4, numerals are inscribed upon the front face of the block in order to indicate the relative dis- 75

tances of the edge faces from the axis of the block. The edge face indicated by the zero is closest to the axis of the block and the numerals opposite the other edge faces, respectively, measure in thirty-seconds of an inch the extent by which the distance of each of said faces from the axis of the block exceeds the distance from said axis of the face indicated by the zero. The distance of said edge faces from the axis of the block progresses by uniform steps, the progression beginning with the face indicated by the zero and ending with the face indicated by the numeral 7. The progression advances in numerical order from 0 to 7 as indicated by the numerals inscribed upon the front face of the block. It will thus be seen that the progression is alternately clockwise and counterclockwise. The shank 40 of the crease finder 48 is provided with a forwardly extending shoulder 98 (Fig. 2) which is arranged to abut against the block 96 in order to locate the crease finder in adjusted position. The location of the tack 30 lengthwise of the shoe is varied by adjusting the longitudinal position of the shoe relatively to the machine. This adjustment is effected by varying the position of the anvil 20. In the illustrated machine this adjustment is afforded by arranging the carrier 34 and the parts associated therewith to slide lengthwise of the shoe. Accordingly, there is provided a horizontal stud 100 (Fig. 6) extending rearwardly from the rear face of the carrier 34 and arranged to be received within a socket 102 provided in the swinging frame 26. Preferably, the adjustment of the carrier 34 is effected by a screw 104 threaded into a tapped socket in the swinging frame 26 and provided with a round head 106 which has formed therein an annular groove 108 within which is located a bifurcated lug 110 which extends downwardly from the under surface of the carrier 34. The carrier may be secured in adjusted position by a draw bolt 112 arranged to engage the stud 100.

In order that the cutting edge of the knife 14 may register accurately with the cutting edge of the anvil 20 a spacing block is provided between the under surface of the carrier 34 and a forward extension 81 of the swinging frame 26 (Fig. 6) whereby the carrier is prevented from rocking in its supporting socket 102 in the swinging frame 26. In the illustrated machine the spacing block is in the form of a wedge 82 (Fig. 5) mounted in an inclined groove 83 in the under surface of the carrier 34 (Fig. 8). The wedge 82 is adjustable longitudinally thereof by means of a screw 84 threaded into a lug 86 extending downwardly from the outer end of the wedge 82 and provided with a round head 88 arranged to engage within a groove 90 formed in the under surface of the carrier 34. It is apparent that the screw 84 may be actuated to advance the wedge 82 in order to take up the space between the under surface of the carrier 34 and the supporting surface of the swinging frame 26.

The operation of the machine, in so far as it relates to the present invention, is as follows. The necessary adjustments having been made to effect the desired location of the tack 30, the shoe to be operated upon is inserted into the machine and moved rearwardly thereof until it is arrested by the engagement of the anvil 20 with the end of the inseam. The clutch is then tripped to start the machine whereupon the knife 14 is moved downwardly and then rearwardly of the shoe carrying with it the cam roll 78 which actuates the cam lever 50. While the welt is

being cut the cam roll 78 travels through a dwell in the cam slot 80. The anvil is braced for the cutting operation by a shoulder 113 (Fig. 8) formed in the welt support 22 and arranged to engage a rearwardly extending lip formed in the anvil. The knife assembly continues to travel rearwardly of the shoe after the welt has been butted, bringing the roll 78 into engagement with the inwardly curved portion 114 of the cam slot 80 (Fig. 2) and swinging the cam lever 50 outwardly, thereby withdrawing the anvil 20 from a position of alinement with the tacker 24. The tacker 24 then moves from its initial position, as shown in Fig. 1, downwardly in a path inclining inwardly toward the shoe bottom and comes to rest with its nozzle 116 in pressing engagement with that portion of the margin of the upper from which the anvil was withdrawn. The tack 30 is then driven and thereafter the operating instrumentalities are returned to their respective initial positions for a repetition of the cycle above described.

Having thus described my invention, what I claim as new and desire to secure by Letters Patent of the United States is:

1. In a welt butting machine, means for fastening the margin of the upper to the insole in the region of the heel breast line, and co-operating welt butting cutters one of which is initially positioned in the path of movement of the fastening means and movable transversely of the shoe out of said position.

2. In a welt butting machine, means for fastening the margin of the upper to the insole in the region of the heel breast line, and cooperating welt butting cutters both of which, during the welt butting operation, are positioned in alinement with the fastening means and both of which are movable out of alinement with said fastening means after the welt has been butted and before the fastener is inserted.

3. In a welt butting machine, a tacker for fastening the margin of the upper to the insole in the region of the heel breast line, and welt butting cutters including an anvil which is initially positioned in alinement with the tacker and movable transversely of the shoe in order to bring it out of alinement with the tacker.

4. In a welt butting machine, a tacker for fastening the margin of the upper to the insole in the region of the heel breast line, welt butting cutters including an anvil which is positioned initially in alinement with the tacker, and means operable after the welt has been butted and before the tack is driven to move the anvil out of alinement with the tacker.

5. In a welt butting machine, a tacker for fastening the margin of the upper to the insole in the region of the heel breast line, welt butting cutters comprising a knife and an anvil arranged in shearing relation to each other said anvil being positioned initially in alinement with the tacker, knife actuating mechanism, and means operated by the knife actuating mechanism to withdraw the anvil transversely of the shoe after the welt has been butted and before the tack is driven.

6. In a welt butting machine, welt butting cutters and a support therefor, said cutters including an anvil constructed and arranged for movement relatively to its support transversely of the shoe.

7. In a welt butting machine, welt butting cutters and a support therefor, said cutters includ-

- ing an anvil constructed and arranged for movement relatively to its support transversely of the shoe, and means operated after the welt has been butted to withdraw the anvil transversely 5 of the shoe.
8. In a welt butting machine, a crease finder, and welt butting cutters including an anvil arranged for movement transversely of the shoe relatively to the crease finder.
10. 9. In a welt butting machine, a support for one end of the welt, a crease finder, and welt butting cutters including an anvil arranged between the welt support and the crease finder for sliding movement transversely of the shoe.
15. 10. In a welt butting machine, a support for one end of the welt, and welt butting cutters including an anvil which is arranged to slide transversely of the shoe relatively to the support, said welt support being constructed and arranged to 20 brace the anvil heightwise of the shoe for the cutting operation.
11. In a welt butting machine, a support for one end of the welt and welt butting cutters including an anvil arranged for movement transversely of the shoe relatively to the support, the upper surfaces of the support and the anvil being disposed in a common plane, and means for supporting the anvil upon the welt support comprising a lip formed in the anvil and arranged to 25 overlie a shoulder formed in the support.
12. In a welt butting machine, a support for one end of the welt, a crease finder, welt butting cutters comprising a knife and an anvil which is arranged to slide transversely of the 30 shoe between the welt support and the crease finder, knife actuating mechanism, and means actuated by the knife actuating mechanism to withdraw the anvil transversely of the shoe after the welt has been butted.
40. 13. In a welt butting machine, a tacker for fastening the margin of the upper to the insole in the region of the heel breast line, a crease finder movable with the tacker transversely toward and from the shoe and adjustable relatively to the tacker in the direction of movement of the crease finder, and a gage for locating the crease finder in any one of a series of predetermined positions relatively to the tacker.
14. In a welt butting machine, a tacker for fastening the margin of the upper to the insole 10 in the region of the heel breast line, a crease finder movable with the tacker transversely toward and from the shoe and adjustable relatively to the tacker in the direction of movement of the crease finder, and means for locating the 15 crease finder in any one of a series of predetermined positions relatively to the tacker comprising an axially mounted polygonal gage block the edge faces of which are substantially equal in length and arranged at varying distances from 20 the axis of the block.
15. In a welt butting machine, a tacker for fastening the margin of the upper to the insole in the region of the heel breast line, a crease 25 finder movable with the tacker transversely toward and from the shoe and adjustable relatively to the tacker in the direction of movement of the crease finder, and means for locating the crease finder in any one of a series of predetermined positions relatively to the tacker comprising an axially mounted polygonal gage block the edge faces of which are substantially equal in length and arranged at varying distances from 30 the axis of the block, the progression of said edge faces about the axis of the block from the edge face nearest said axis to the edge face farthest therefrom being alternately clockwise and counterclockwise.

BENJAMIN B. BLANCHARD. 40
